(57) **CLAIM**

The ornamental design for a hearing aids and charging case set as shown and described.

DESCRIPTION

FIG. 1 is a perspective view of the hearing aids from a hearing aids and charging case set showing the claimed design;

FIG. 2 is another perspective view of the hearing aids thereof;

FIG. 3 is a front elevational view of the hearing aids thereof;

FIG. 4 is a rear elevational view of the hearing aids thereof;

FIG. 5 is a left side view of the hearing aids thereof;

FIG. 6 is a right side view of the hearing aids thereof;

FIG. 7 is a top plan view of the hearing aids thereof;

FIG. 8 is a bottom plan view of the hearing aids thereof;

FIG. 9 is a perspective view of the charging case thereof;

FIG. 10 is another perspective view of the charging case thereof;

FIG. 11 is a front elevational view of the charging case thereof;

FIG. 12 is a rear elevational view of the charging case thereof;

FIG. 13 is a left side view of the charging case thereof;

FIG. 14 is a right side view of the charging case thereof;

FIG. 15 is a top plan view of the charging case thereof;

FIG. 16 is a bottom plan view of the charging case thereof;

FIG. 17 is a view of the closed claimed design in use thereof; and,

FIG. 18 is a view of the open claimed design in use thereof. The broken lines depict portions of the hearing aids and charging case set that form no part of the claimed design.

1 Claim, 18 Drawing Sheets
